INVENTOR,
James McLaughlin,
BY
P. G. Siggers.
ATTORNEY.

UNITED STATES PATENT OFFICE.

JAMES McLAUGHLIN, OF PONTARDULAIIS, WALES.

SHACKLE, CHAIN COUPLING, OR THE LIKE.

1,419,974.

Specification of Letters Patent. Patented June 20, 1922.

Application filed March 10, 1921. Serial No. 451,293.

To all whom it may concern:

Be it known that I, JAMES McLAUGHLIN, a subject of His Majesty the King of England, and resident of Pontardulais, in the 5 county of Glamorgan, Principality of Wales, have invented certain new and useful Improvements in or Relating to Shackles, Chain Couplings, or the like (for which I have filed an application in Great Britain, February 17, 1919, Patent No. 142,942), of which the following is a specification.

This invention relates to shackles, chain couplings or the like and more particularly to improvements in shackles employed on 15 colliery tramways or the like of the type wherein a pin is rotatably mounted and adapted to move vertically in eyes formed in the outer ends of a substantially U-shaped member, a coiled spring being arranged between the head of the pin and one of the 20 ends of the member to normally retain a projection on the pin in a recess cut in one of the eyes of the said member, a slot being provided at an angle to the recess in the 25 said eye so that the pin, when turned, can be raised until its extension engages in another recess cut in the other eye to enable the shackle to be uncoupled.

The object of this invention is to provide 30 means to enclose the spring of shackles of the above type so as to eliminate the danger of workmen catching their fingers therein and also to prevent the entrance of foreign matter such as coal or stones between the coils 35 of the spring.

With this and other objects in view the invention consists in movably mounting on the pin of a shackle of the above described type a sleeve slidable in a handle or knob 40 formed on the head of the pin and arranging the coiled spring within the handle or knob so as to prevent the entrance of dirt to the said spring.

The invention will now be described with 45 references to the accompanying, in which:—

Figure 1 is a side elevation of one form of shackle constructed according to the invention.

Figure 2 is a similar view showing the 50 shackle in open position;

Figure 3 is a longitudinal section;

Figure 4 is an end view;

Figure 5 is a similar view to Figure 4 of a slightly modified construction, and

Figure 6 is a similar view to Figure 3 of 55 the modification shown in Figure 5.

As shown in Figures 1 to 4 the shackle comprises a substantially U-shaped member *a*, to which is attached the links *b* of a coupling chain, and a pin *c* adapted to move 60 vertically in eyes *d* formed in the outer ends of the U-shaped member *a*. The pin *c* is formed or provided at or adjacent to its lower end with a stop or projection *e* which is normally adapted to, lie in a slot or recess 65 *f* cut in the underside of the lower eye of the shackle member *a*. A vertical groove *g* is also cut or formed preferably in the opposite side of the eye *d* through which groove *g* the stop or projection *e* is passed when the 70 pin *c* is raised to release the shackle. The head of the pin *c* is formed or provided with a handle or knob *h* and within this knob *h* and slidably mounted on the pin *c* is a flanged sleeve *i*. Within the sleeve *i* 75 and surrounding the pin *c* is arranged a coiled spring *j* which is adapted to engage at one end against an inner flange *k* on the sleeve *i* and at its other end against the base of a recess *l* formed between the pin 80 *c* and the knob *h*. The sleeve *i* is formed with a slit or hole *m* to enable the spring *j* to be lubricated when desired, or oil to be contained within the sleeve *i* to lubricate the pin *c* when the knob *h* is forced down to 85 lock the shackle. A slot or recess *n* is cut in the underside of the upper eye *d* of the U-shaped member *a* for the reception of the stop or projection *e* on the pin *c* when the said pin *c* is raised to release the shackle, 90 as shown in Figure 2.

In operation and when it is desired to couple up colliery trams or the like, the knob *h* is turned and raised to turn and raise the pin *c* connected thereto, in the U-shaped 95 member *a* until the projection *e* on the pin *c* is disposed in the slot or recess *n* formed in the upper eye *d* of the shackle *a*. The shackle *a* can now be moved into position with the eye plate or link *b'* on the colliery 100 tram and coupled up by allowing the pin *c* to drop. The projection *e* on the lower end of the pin *c* will pass through the slot or groove *g* cut in the lower eye of the U-shaped member *a*. The knob *h* is then 105 pressed down to compress the spring *j* and rotated through an angle of 180° until the projection *e* on the pin *c* is adjacent to the

recess *f* cut in the opposite side of the lower eye *d*. When the knob *h* is released the pin *c* will be raised by its spring *j* and the projection *e* on the pin *c* will engage in the 5 said recess *f* to lock the shackle.

In a modified construction as shown in Figures 5 and 6, the flanged sleeve *i* is formed or provided with a vertical rib or projection *o* which is adapted to engage in 10 a socket or recess *p* formed in a vertical enlargement *q* on the side of the knob *h*. This socket *p* is arranged on the opposite side of the pin *c* to the lower projection *e* on the pin *c*. Thus the flanged sleeve *i* 15 will be rotated with the knob *h* and the position of the enlargement *q* thereon will indicate when the knob *h* can be released to allow the lower projection *e* on the pin *c* to engage in the recess *f* to lock the shackle.

20 What I claim is:—

1. A shackle comprising a pin rotatably mounted and movable vertically in eyes formed in the outer ends of a substantially U-shaped member, a coiled spring arranged 25 between the head of the pin and one of the ends of the member a projection on the pin, slots in the said eyes adapted to receive the projection, a sleeve movably mounted on the pin and slidable in a handle formed on 30 the head of the pin, the coiled spring being arranged within said handle, for the purposes described.

2. A shackle comprising a pin provided 35 with a head and rotatably mounted and movable vertically in eyes formed in the ends of a substantially U-shaped member, a circular flange depending from the head, a sleeve slidably mounted within the circular flange and on the pin and provided with a flange 40 resting on one of the arms of the U-shaped member, a coiled spring on the pin having abutting relation with the head of the pin and the flange on the sleeve, and a lug on

the end of the pin adapted to be seated in slots formed in the ends of the U-shaped 45 members.

3. A shackle comprising a pin provided with a head and rotatably mounted and movable vertically in eyes formed in the ends of a substantially U-shaped member, a coiled 50 spring on the pin tending to force the pin outwardly from the eyes, a lug on the end of the pin adapted to be seated in slots formed in the ends of the U-shaped member, the spring maintaining the lug in the slot 55 of an arm of the U-shaped member, said arm being provided with a groove through which the lug slides when the pin is moved to position the lug in the slot of the other arm and to open the shackle.

4. In a shackle as claimed in claim 1, the provision of co-operating guides on the said sleeve and handle, substantially as and for the purpose described.

5. A shackle comprising a pin provided 65 with a head and rotatably mounted and movable vertically in eyes formed in the ends of a substantially U-shaped member, a sleeve slidably mounted within the head and provided with a flange, a coiled spring on the 70 pin having abutting relation with the head and flange, complementary means on the head and sleeve to cause rotation of the sleeve with the head, a lug on the end of the pin adapted to be seated in slots in 75 the arms of the U-shaped member, one of said slots adapted to be engaged by the lug for locking the pin in position and diametrically disposed to the complementary means, the normal position of the complementary means indicating the seating position of the lug in said slot.

In testimony whereof I have hereunto signed my name.

JAMES McLAUGHLIN.
